UNITED STATES PATENT OFFICE

JAMES M. KENDALL, OF WOODBURY HEIGHTS, NEW JERSEY, ASSIGNEE, BY MESNE ASSIGNMENTS, TO RADIO CORPORATION OF AMERICA, OF NEW YORK, N. Y., A CORPORATION OF DELAWARE

SOUND RECORDING AND REPRODUCING UNIT

Application filed March 12, 1931. Serial No. 521,936.

My invention relates to sound recording and reproducing apparatus, and it has particular relation to apparatus of the type adapted to employ wax or other suitable

tend to diminish, the amplitude of its vibrations, thereby varying the character of the signal being translated, from that desired and intended.

55

5 sound record tablets or disks having a mechanical sound track in a surface thereof.

By an analysis of the above and other similar objectionable influences I have found that a major portion of the vibrations are torsional vibrations of the translating device and suspension means or arm, the vibrations occurring about the axis of the suspension arm or 60 an axis approximately determined by and extending through the center of mass of the translating device itself and the pivotal connection of the arm with its supporting pedestal.

65

More specifically, my invention relates to that unitary portion of a sound recording and reproducing apparatus of the above type 10 which operates directly in connection with the record tablet or disk to finally record in, or initially reproduce sounds from, the groove or sound track. This unitary portion of the apparatus, which may be termed the 15 sound recording and reproducing unit, includes a suitable device for translating vibratory or electrical impulses into a corresponding motion of a stylus with which the device is provided, for recording in the sound track 20 or record groove, or for translating motion of the stylus derived from the sound track or record groove into corresponding vibratory sound or electrical impulses.

I have found that an undesirable torsional resonance causing vibration, common to many types of suspension arms, occurs within a range of substantially 90 to 150 cycles. Resonance is also encountered to some extent, 70 at frequencies above this range. Resonance within this range is particularly troublesome since it includes the natural period of vibration to which a large number of the more commonly used cabinets or housings for the apparatus are responsive. Vibrations produced through the translating device, when reproducing, for example, are communicated to the cabinet through the sound output device or 75 loud speaker located therein, and may regeneratively be transmitted from the cabinet to the translating device through the suspension means and its point of connection with the cabinet. Also vibrations, caused by 80 motor means, and other vibration generating apparatus included in the same assembly, 85 may be impressed upon the stylus through the suspension means.

80

85

90

95

100

The translating device is carried in operative relation to the record disk whereby the stylus is permitted to follow the sound track, by a suitable supporting means or suspension arm which is pivotally mounted to permit the translating device to be movable freely both 30 in a plane parallel with and also in a direction perpendicular to the surface of the record disk in which the sound track is located. The suspension arm is, of necessity, elongated axially whereby it supports the translating 35 device over the active portion of the record surface from a fixed point of support.

With sound translating units heretofore known, difficulty has been experienced in eliminating the distorting effect upon the 40 sound translation of vibrational forces acting upon the translating device.

I have found that distorting influences upon the sound translation may often be caused by communication of the vibrations 45 of the stylus to the translating device itself and to the suspension means, and the reflection of these vibrations back to the stylus.

The reflected vibrations, like others when 50 in phase with those of the stylus, tend to augment, and when out of phase therewith

Because of these influences, in operation, the recording stylus may frequently be dislodged from one turn of the sound track or groove to another, being advanced or retracted in its course and thus skipping a portion of the record or being caused to repeat a portion already transcribed. This difficulty occurs particularly with vibrations of low frequency and great amplitude.

From the foregoing it will be seen that the translating device may be subjected to vibratory influences from the stylus and the asso-

ciated apparatus, or either of them, the external vibratory forces being transmitted from the fixed point of support through the suspension means, while vibration from the stylus is received directly. It will be understood that, when the stylus is engaged with the record track or groove, the above described resonant or other undesired vibratory movement of the translating device tends to cause undesired relative movement between the stylus and said device, thereby introducing distortion into the recording or reproduction of the sounds.

It is, therefore, a primary object of my invention to provide an improved sound recording and reproducing unit, including a sound translating device and a suitable support therefor, which obviates the above described and similar difficulties heretofore experienced with units of that character, and which is simple in construction and adapted for manufacture at low cost.

More specifically, it is an object of my invention to provide a sound recording and reproducing unit, including a translating device and a support therefor, of such construction that the translating device will not partake of, or be influenced to vibrate, by the vibrations of the stylus bar or of the associated cabinet or other supporting structure of the apparatus.

In carrying out my invention, I provide an improved unit that is so constructed and the parts are so arranged that the effect of vibrations from sources external to the unit and the vibrational influences generated in the unit, as for example, by the stylus, are prevented from affecting the recording and reproducing action of the translating device and causing distortion of the recorded or reproduced sounds.

I, also, so relate the moment of inertia of the unit about the axis of the suspension means, that is, the torsional axis of vibration or the longitudinal axis between the point of support and the translating device, that the resonance frequency of vibration about such axis of the unit is below the frequency range of the sounds to be recorded or reproduced.

In the present preferred embodiment of my invention as shown and described herein-after, the translating device itself is closely associated with a stabilizing or mechanical impedance means having a relatively high moment of inertia and relatively low intrinsic weight or mass, and is flexibly mounted in connection with suitable supporting pivot means whereby, as the stylus of the translating device follows the sound track or groove of the record, the translating unit tends to remain stationary with respect to the stylus and is prevented from being responsive to any vibrational influence transmitted to it from the stylus within the frequency range of the sounds to be recorded or reproduced,

or from vibrational forces which may be present in the supporting means and which may be transmitted to it therefrom.

The invention will be better understood, however, from the following description when taken in connection with the accompanying drawings, and its scope will be pointed out in the appended claims.

In the drawings, Fig. 1 is a full-size plan view of a recording and reproducing unit, including an electric translating device and suitable suspension means therefor, embodying my invention and applied to a phonograph apparatus adapted to use disk records; Fig. 2 is a similar view of the opposite or lower side of a portion of the suspension means shown in Fig. 1; Fig. 3 is a view in cross section taken on line 3-3 of Fig. 1; Fig. 4 is a view in perspective of a detail of the suspension means shown in the preceding figures; Fig. 5 is a front end view of the portion of the suspension means shown in Fig. 2; and Figs. 6, 7, 8 and 9 are cross sectional views taken respectively on lines 6-6, 7-7, 8-8 and 9-9 of Fig. 3. All of the figures of the drawings are drawn to the same scale and like parts throughout bear the same reference numerals.

Referring to the drawings, the sound recording and reproducing unit of the present example includes as its three major portions, a translating device 10, a suspension arm 11 for the translating device, and a supporting pedestal 12 for the suspension arm. The translating device is provided with a stylus 13 which is adapted to engage a sound track or record groove 14 of spiral form provided in a surface of a suitable record disk 15. The record disk is carried on a suitable rotary turntable 16, forming part of the apparatus associated with the recording and reproducing unit, disposed in a cabinet or enclosing structure indicated by a mounting or motor board 17, on which also the supporting pedestal 12 is provided with a fixed pivot mounting in the form of a base plate 18 secured to the motor board.

In the present example, the translating device is of the electric pickup type having, as indicated in Fig. 3, an armature 19 pivotally mounted with the stylus 13 to vibrate therewith under the action of the sound track, and an electric pickup coil 20 surrounding the armature for receiving from or transmitting to the armature and the stylus, impulses incident to the recording or reproduction action of the device. The pickup coil is provided with suitable leads 21 carried through the suspension arm and having terminals 22 for connection with associated apparatus (not shown).

The reproducing unit is removable from the suspension arm and is connected therewith by a suitable neck or projection 23 inserted into one end of the arm. A suitable

releasable terminal connection indicated at 24 is provided for the leads 21.

The suspension arm is of such length that the translating device 10 may move over the

- 5 record surface about a fixed point of support provided by the pedestal 12, in a plane parallel to the record surface and also may move in a direction generally perpendicular thereto, whereby the translating stylus 13 may 10 follow the spiral sound track and the translating device may move vertically in response to changes in the level of the record surface. To provide this arrangement, the suspension arm is pivotally connected with the supporting 15 pedestal by a fulcrum or pivot pin 25 providing a horizontal pivot axis extending through the pedestal and the arm at a point adjacent the end of the suspension arm opposite to the end to which the translating device 20 is connected. The supporting pedestal is provided with a vertical pivot pin 26 which is journaled in a suitable bearing 27 provided in the base plate 18. It will be noted that the pivot pin is hollow whereby the leads 21 may 25 be extended therethrough to a point below the supporting structure or motor board 17. By the arrangement shown, the leads are effectively concealed throughout their length.

- The suspension arm is provided with a suitable counterweight 28, on the opposite side of the pivot pin or fulcrum 25 from the translating device, of such mass or weight that it reduces the pressure of the stylus, caused by the weight of the translating device and the 35 suspension arm, to a desired value such that the stylus is permitted accurately to follow the record groove without injury thereto.

- Referring particularly to Figs. 1 and 3, it will be seen that lateral vibration of the stylus 40 13 and a lateral vibration of the motor board 17 may operate to impart to the translating device 10 a corresponding vibratory motion, since both the stylus and the connection means with the motor board or supporting structure 45 provide a leverage along a line X—X, with respect to the axis or torsional axis of the suspension arm indicated generally by a line Y—Y, Fig. 3. This axis is that indicated in Fig. 1 by the dot-and-dash line on which the

- 50 section of Fig. 3 is taken, being the central axis of the recording and reproducing unit. This axis extends longitudinally of the suspension arm and may be considered as the torsional axis of vibration of the unit.

- 55 In the usual apparatus of this character the suspension arm is rigidly mounted and is not provided with means for preventing torsional vibratory forces from being transmitted or imparted to the translating device along or about the above axis. In accordance with my invention, however, I provide not only flexibility in the suspension arm or suspension means between the translating device and its pivotal point of support in the suspension arm, but also mechanical impedance means

adjacent the translating device which cooperate to prevent torsional vibration of the translating device from either of the sources above mentioned.

Resonance vibrations are almost always 70 possible where a mass, having a high moment of inertia about an axis of vibration, is rigidly mounted at one point. In torsional resonance, the moment of inertia is due to the mass of the translating device, taken about an axis substantially determined by the center of mass of the translating device, and the pivotal mounting of the suspension means therefor. This is for the reason that the angle of the stylus, as indicated in Fig. 3, and the 75 action of the sound track tend to impart a rotary or torsional movement to the device and the suspension means along said axis, which substantially is that of the suspension means. The rigidity, in such cases, often lies 80 in the stylus mounting and in the suspension means.

I have found that the objectionable torsional resonance resulting from the combination 85 of moment of inertia and rigidity or stiffness, as set forth above may be overcome by reducing the natural frequency of the unit about the axis of torsional resonance to well below the lowest frequency to be reproduced. This frequency may be changed by varying either the 90 stiffness of the mounting at a certain point or by varying the moment of inertia about the axis of torsional resonance or vibration, or by changing both of these factors together, 95 in proper relation to each other as in the present preferred embodiment of my invention 100 shown and described herein. The torsional stiffness along the axis of the suspension means may be changed materially and the mass associated with the translating device may also be varied, the former being 105 preferably decreased and the latter increased as will now be explained.

In the present example, the flexibility in 110 the mounting means between the translating device and the pivotal point of support is provided in the suspension arm itself in a region indicated generally by the numeral 29 adjacent the pivotal point of support and between it and the translating device. The impedance or damping means is provided by increasing the mass of the supporting means 115 adjacent the translating device. The increase of mass is provided, preferably, in the manner indicated in the drawings, by a pair of spaced weights 30—30 of equal mass located at equal distances from the torsional axis of vibration of the unit or, in the present example, of the suspension arm.

The weights providing the increased 120 stabilizing mass, or mechanical impedance means, are relatively widely separated, substantially to the limits imposed by the appearance of the completed design and by a 125 consideration of convenience of operation.

In accordance with well known physical laws, the amount of inertia about the torsional axis of vibration is thus increased to a desired value without materially increasing the mass attached to the translating device.

I have found that it is preferable that the mass included in the moment of inertia shall be a part of, integral with, or at least very rigidly secured to, the translating device itself, as in the present example. The effect of this arrangement is that the translating device is held stationary by the mass impedance, against the influence of any change of velocity of the stylus, and when forces are applied to the stylus and therefore to the sound translating device in which it operates, the stylus is deflected or moves before the translating device can respond with a like or resonant movement. The mass of the translating device being flexibly supported, will thus be prevented from vibrating about the axis of vibration in response to the vibrations of the stylus. Hence no vibration and distortional influence will be introduced into the sound translation process. The stylus will not jump or be thrown out of the groove and no repeating or skipping of the sound record will occur.

It is also important that the mass of the assemblage should be increased as little as possible, in attaining the required moment of inertia and, to this end, weights are attached to the suspension arm spaced from and on opposite sides of the axis of vibration of the assemblage. It is obvious that in an apparatus of this character the lateral spacing of the weights relative to said axis has certain limitations imposed by appearance hereinbefore mentioned, and convenience of operation. It is also desirable, in order that the pressure exerted by the assemblage on a record tablet shall not be increased above a desired amount, the weight or mass providing the moment of inertia be suitably counterbalanced. In the present example, the increased weight imposed by the inertia or impedance means is suitably counterbalanced by properly proportioning the counterweight 28, as by increasing its weight or leverage with respect to the pivot axis 25.

It is desirable to provide a construction which is of pleasing appearance, adapted to conceal the inertia or stabilizing mechanical impedance means and counterbalancing weights, and to provide a flexible connection between the translating device and the pivotal point of support. To this end the suspension arm is formed of thin sheet material struck up along its edges to provide an integral marginal flange 31 which, when in use, extends downwardly to conceal the weights, substantially as indicated in Figs. 1, 2, and 3 of the drawings. The body of the arm is flared at its ends and is reduced between its ends to a narrow neck of U-shape

transverse section, substantially as indicated in Fig. 7, this section being taken, as indicated in Fig. 3, through the region of flexibility 29.

The flared portion of the suspension arm to which the translating device is to be connected, is provided with a frontal opening, indicated in Fig. 5 at 32, and with a central opening 33 adapted to be closed by a suitable escutcheon plate or cover 34.

It will be seen that the suspension arm is in the form of a flanged plate adapted to be struck up from a single piece of sheet material whereby it may be manufactured at low cost and, by its form, it provides not only suitable cover means or a housing for the weights, but a thin narrow flexible section 29 adapted to give the unit the desired flexibility between the translating device and its pivotal point of support. Furthermore the section of the arm is adapted to fit over and conceal from view the upper end of the supporting pedestal 12, and to be pivotally connected thereto by the simple pivot pin 25. The construction of the pivot connection is shown more clearly in Fig. 8.

The counterbalance weight 28 is secured to the arm or within the arm by a single rivet 35. However, in order more accurately to locate the inertia or impedance weights 30-30, the latter are mounted in a wing-shaped frame or yoke 36 in the wings or ends of which are secured the weights 30. The yoke 36 is used also to gain rigidity in attaching the weights 30-30 to the translating device. As indicated in Fig. 2, the wings of the frame are adapted to lie in the frontal and more widely flared portion of the arm, and are secured thereto by any suitable means such as by mounting tabs 37, 38 spot-welded as indicated at 39, Fig. 2, to the interior of the arm. The frame is provided with a central opening 40 through which the connection for leads 21 is taken and is further provided with a tab 41 which provides a connection with the translating device and operates with the arm to provide one surface of the frontal opening 32 for the mounting neck of the translating device, the tab 41 being arranged to lie in spaced relation to and opposite the upper surface of the suspension arm at the opening 32 whereby the neck of the translating device is received between said tab and said surfaces in the opening. A bolt or other suitable fastening means 42 may then be passed through aligned openings 43 in the neck and in the tab and suspension arm for securing the translating device to the arm.

It will be seen that with the frame 36 secured to the arm at three spaced points provided by the tabs 37 and 38, it provides a rigid bracing means for the arm and a rigid connection between the impedance or inertia weights 30 and the translating device. It

thus becomes a unitary part of the arm itself. The frame serves not only as a mounting means for the inertia weights but also as a template for permitting the accurate location of the weights with respect to the torsional axis of vibration of the arm.

By forming the translating unit assemblage as described above, a suitable moment of inertia is provided about the axis of torsional vibration of the arm without materially increasing the weight thereof. By narrowing the construction of the suspension arm in the region 29 of the pivotal connection at 25 with the pedestal 12, between the translating device and the pivotal connection, the effect of any stiffness of this connection, on the tendency of the suspension arm to vibrate, is materially diminished as compared with that of similar apparatus of known construction.

In my improved device or unit, the connection between the suspension arm and its supporting pedestal may also be made with less attention to machining and fitting of the parts than has been heretofore possible. A loose pivot connection at 25 may be employed without adversely influencing the effectiveness of the unit. In fact, a loose connection has certain advantages over a more exact construction as aiding the flexibility. It will therefore be seen that the present device may be manufactured with the exercise of only ordinary mechanical skill, thereby reducing the cost of production.

35 I claim as my invention:

1. In a sound recording and reproducing apparatus, a translating device, a suspension means therefor having a point of support in spaced relation to said device, a connection 40 in said suspension means flexible about an axis extending through said device and said point of support and between said device and said support, and means connected with said device and located more adjacent thereto than said point of support providing a relatively high moment of inertia about said axis.

2. In a sound recording and reproducing apparatus, a translating device, suspension means therefor having a point of support in spaced relation to said device, a connection 50 in said suspension means flexible about an axis extending between said point of support and the translating device, and inertia means carried by said suspension means and connected with said device adjacent thereto, said means having a moment such that it reduces the natural frequency of vibration of said device and suspension means about said axis below the frequency range of the sound energy to be translated by said device.

3. In a sound recording and reproducing apparatus, the combination with a sound translating device having a vibratory element, and an apparatus supporting means, 65 of a flexible suspension arm for said device

mounted on said supporting means, an inertia means connected with said device and having a moment such that the arm and said device are caused to be out of resonance with vibrational forces about the axis of the arm imparted to said device from said element and from vibrational forces existing in said supporting means.

4. A sound recording and reproducing unit, including in combination, a translating device, means adapted to provide a pivotal support therefor, means providing a connection between said supporting means and said device, said connection being flexible about a torsional axis of vibration extending through said device and said supporting means, and a mechanical impedance means connected with said device adjacent thereto, said last named means having a relatively low mass and high inertia about said torsional axis of vibration.

5. A sound recording and reproducing unit including a translating device and support therefor, characterized by the fact that a mass having relatively high moment of inertia about an axis extending through said unit and the support is embodied in the unit adjacent to the translating device in direct connection therewith, and that a region of flexibility is provided about said axis between the translating device and the support.

6. The combination with a sound translating device having a movable stylus and a torsional axis of vibration about which movement of the stylus tends to set up movement 100 of the translating device, of means directly connected with and located adjacent to the translating device, providing a relatively high moment of inertia about said axis, and means flexible about said axis providing a support for said device and first named means.

7. In sound reproducing apparatus and the like, the combination with a sound translating device, of a supporting means for said device providing a flexible mounting for said device in said apparatus, and inertia means directly connected with and located adjacent to said device, providing relatively high mechanical impedance to vibrational movement of said device.

8. The combination with a sound translating device having a movable stylus, and a torsional axis of vibration about which vibrational movement of the stylus tends to set up a corresponding movement of the translating device, of means directly connected with and located adjacent to the translating device providing a relatively high moment of inertia about said axis, a support for said device in spaced relation thereto, and means providing a region of flexibility about said axis between said translating device and said support.

9. In a sound recording and reproducing unit, a support, a translating device, an arm 130

connected at one end with said device and pivotally connected adjacent its opposite end with the support, and inertia means associated directly with said device having a mass equally distributed on opposite sides of a longitudinal axis of the unit, which axis extends through the translating device and the pivotal connection with the support, and said arm having a region of flexibility about said axis between said inertia means and said support.

10. In a sound recording and reproducing unit, a support, a translating device, an arm rigidly connected at one end with said device and pivotally connected adjacent its opposite end with the support, and inertia means having a mass equally distributed on opposite sides of a longitudinal axis of the unit extending through the translating device and the pivotal connection with the support, said 15 arm having marginal flanges providing a channel of U-shaped transverse section between its ends, and said channel being reduced in transverse section to provide a region of flexibility about said axis between 20 said translating device and inertia means and said pivotal connection.

11. In a sound recording and reproducing unit, a support, a translating device, an arm rigidly connected at one end with said device 25 and pivotally connected adjacent its opposite end with the support, a yoke rigidly secured to the translating device transversely of a longitudinal axis of the unit, spaced weights of equal mass carried by the yoke on opposite 30 sides of said axis in equal spaced relation thereto, said arm having marginal flanges providing a channel of U-shaped transverse section between said ends, and said channel being reduced in transverse section to provide 35 a region of flexibility about said axis between said translating device and weights and said pivotal connection with the support.

12. The combination with a sound translating device having a body portion and an operating element relatively movable with respect 40 thereto for the translation of sound energy, of a suspension means for said device, a support for said suspension means, and means for preventing distortion in the translation of sound 45 energy by undesired relative movement between said body and element, said means including a section in said supporting means providing a region of flexibility adjacent the support about an axis extending along said 50 suspension means, and a mechanical impedance means adjacent to and connected with said device having a relatively high moment of inertia about said axis.

13. In a sound translating apparatus having 55 a supporting structure subject to vibration and a translating device having a vibratory element, of a stabilizing means for the translating device, said means having a relatively high moment of inertia about the axis of vibration of the translating device, and be-

ing rigidly connected directly with said device, and supporting means for said translating device arranged to provide a flexible connection between said translating device and said supporting structure.

14. The combination with a sound translating device having a movable stylus, and supporting means therefor, said translating device and the supporting means being arranged in spaced relation to each other, of means for preventing vibratory movement of said translating device about an axis extending through said device and said supporting means in response to vibratory forces generated by movement of said stylus and vibratory forces transmitted through said supporting means, said vibration preventing means including a mass having a relatively high moment of inertia about said axis and relatively low intrinsic weight, and a connection providing a region of flexibility about said axis between said device and said supporting means.

15. A sound recording and reproducing unit including a translating device and support therefor, characterized by the fact that a mass having relatively high moment of inertia about an axis extending through said unit and the support is embodied in the unit adjacent to the translating device in direct connection therewith, and that supporting means for the translating device and said mass having a region of flexibility located in spaced relation to said device and said mass is provided in said unit.

16. The combination with an electric pickup device and a suspension arm therefor having with said device a common torsional axis of vibration extending along the arm, of means having a rigid connection with the pickup device for effectively increasing the amount of inertia of said device about said torsional axis of vibration, and said arm providing a region of torsional flexibility about said axis.

17. The combination with an electric pickup device having an axis about which it tends to move in response to vibrational forces, of means for effectively increasing the moment of inertia of the pickup device about said axis, supporting means for said device connected therewith in spaced relation thereto, and suspension means for said device providing said connection and a region of torsional flexibility about said axis intermediate of the inertia increasing means and the supporting means.

18. In combination, an electric pickup device, a pivoted supporting arm to the free end of which the pickup device is affixed, and means carried by the arm for effectively increasing the moment of inertia of the pickup device about a torsional axis of vibration extending through said device and along the arm, said arm having a region of torsional

flexibility intermediate of the inertia increasing means and the pivoted end thereof.

19. In an electric sound recording and reproducing apparatus, the combination of a 5 motorboard, a pickup suspension arm, a supporting pedestal therefor mounted on the motorboard, an electric pickup device having a body mounted on said arm and a movable stylus in said body, means carried by the arm 10 for effectively increasing the moment of inertia of the pickup device about a torsional axis of vibration extending along the arm, and said arm having a region of torsional flexibility between said inertia increasing means 15 and the supporting pedestal.

20. In an electric sound recording and reproducing apparatus, the combination of a motorboard, a pickup suspension arm, a supporting pedestal therefor mounted on the 20 motorboard, an electric pickup device having a body mounted on said arm and a movable stylus in said body, and means for preventing vibratory movement of the body of the pickup device in response to vibratory movement 25 of the stylus and of the motorboard within predetermined frequency ranges of vibration, said means including a mass of intrinsically low weight and relatively high inertia about a longitudinal axis extending through said 30 device and the axis of the arm, said mass being associated directly with the body of the pickup device for effectively increasing the moment of inertia thereof about said axis, and said arm providing a region of torsional 35 flexibility along its length and about said axis between said device and the supporting pedestal.

In testimony whereof, I have hereunto subscribed my name this 9th day of March 1931.

40 JAMES M. KENDALL.
